Samuel Meyerson, West Hempstead, N.Y.

Application June 10, 1957, Serial No. 46,538

Term of patent 7 years

(Cl. D45—4)

FIG. 1

FIG. 2

FIG. 3

FIG. 4

Fig. 1 is a perspective view of an expandable link chain for a bracelet, showing my new design;

Fig. 2 is a top plan view of one of the links of the chain illustrated in Fig. 1;

Fig. 3 is an enlarged sectional view taken on the line 3-3 of Fig. 2; and

Fig. 4 is an enlarged sectional view taken on the line 4-4 of Fig. 2.

The dominant features of my design reside in the portion shown in full lines.

I claim:

The ornamental design for an expandable link chain for a bracelet or the like, as shown and described.
